BEAM HANGER

Henry A. Winland, Lancaster, Ohio, assignor to
 George H. Alten, doing business as Alten's
 Foundry and Machine Works, Lancaster, Ohio

Application May 7, 1934, Serial No. 724,443

4 Claims. (Cl. 74—103)

My invention relates to new and useful improvements in cable bearings for walking beams, often spoken of as "beam hangers."

One of the objects of the present invention is to provide a device of the character described especially designed for application to a walking beam, and furthermore to so construct the beam hanger or cable bearing that there is no possibility of a parted rod or tubing being dropped 10 within the hole should the wire cable break on either side of the hanger.

As is well known in the pumping of wells, especially deep wells, a walking beam is commonly employed, which is pivoted to a support, the 15 power being applied at one end and the beam hanger or cable bearing being supported at the other. Operated by the cable in the hanger is the pump rod or pump polish rod, which reciprocates in a stuffing box, and, of course, it is necessary that the pump rod operate in a 20 vertical manner.

Still another object of the invention, therefore, is to provide a beam hanger that is strong in construction, easily installed, so designed that it 25 insures a straight lift stroke, and finally that should one bight of the cable that supports the rod break the other bight of the cable will be prevented from leaving the cable bearing, thus adding a further factor of safety.

Still another object of the invention is to provide a beam hanger in which all joints may be 30 electrically welded, which beam hanger may be readily and conveniently fastened to a block on the distal end of the walking beam, and which 35 beam hanger may be quickly swung back to clear the hole when pulling or removing the rods or tubing.

With these and other objects in view, the invention consists in certain new and novel arrangements and combination of parts, as will be hereinafter more fully described and pointed out in the claims.

Referring now to the drawing showing a preferred embodiment,

Fig. 1 is a fragmentary side elevation of my improved beam hanger as secured to the end of a walking beam;

Fig. 2 is a front view thereof;

Fig. 3 is a sectional view of a bracing clamp taken on the line 3—3 of Fig. 1, looking in the direction of the arrows;

Fig. 4 is a detail of one of the safety clamps provided, part being broken away for the sake 55 of clearness;

Fig. 5 is a detail sectional view of the beam hanger taken on the line 5—5 of Fig. 2.

Referring now to Figs. 1 and 2 showing a preferred embodiment, there is shown a fragmentary portion 1 of a walking beam which, as is well known, will be pivoted to a support (not shown). To the proximal end of the beam will be applied power for operating the same, this connection not being shown as it is in common use and well known. This beam is preferably made of steel and may be fabricated, consisting of the channels 2 and 3, as shown in Fig. 2, and may have braces, as shown at 4, along its length.

There will be noticed near the end of the beam 15 is provided a block 5 which is securely bolted, as at 6, to the outstanding flanges of the two beams, and it is this block that forms a cradle or bearing for a pintle or trunnion 7, from which is to be hung the beam hanger or cable bearing. 20 After the trunnion has been properly placed within the block, it may be rigidly held in position by the relatively long bolt 8 that, in turn, may be held at its lower end by the plate 9, as may be seen in the several views.

Referring now for the moment to the beam hanger proper, it will be seen that it consists of two arcuate cable guide arms or bearings 10 and 10', whose center would be the pivotal point 25 of the walking beam, these arms 10 and 10' being electrically welded to the respective plates 11 and 12. These latter plates are provided with openings through which the opposite ends of the trunnion will pass to thus adjustably support the beam hanger.

Also extending in an arcuate manner above the trunnion 7 may be seen the plate or crown 13 over which will pass the cable 14, shortly to be described. Supporting this crown 13 may be seen the braces 15 which bear at their lower 40 ends on the pintle 7. I may also provide the two eye bolts 16 to not only hold the cable on the crown but to hold the cable in position.

Referring now for the moment to the cable 14, it consists of what might be termed two bights 45 14' and 14''. It will be noticed that one bight 14' is passed through an opening 17 in the one end of the trunnion while the bight 14'' passes through a like opening 18 in the opposite end of the trunnion.

To prevent the loosing or possibility of dropping the rods or tubing, I provide two clamps 19 and a description of the one is a description of the other. One clamp is secured to the bight 14' just above the trunnion 7 and is locked in 50 55

place by the nuts 20, there being provided a small plate 21 over the ends of the U-shaped member 22, so that on a drawing up of the nuts 20 the cable will be securely clamped in position.

As heretofore mentioned, two of these clamps are provided, so that should the bight 14' of the cable part anywhere up to the trunnion the remaining bight 14" of the cable will still remain

- 10 fastened to the pump polish rod and prevent the loss of the tools or parts. In Fig. 2 I have shown in dotted lines a pump polish rod and the upper extremity of a clamp which, in turn, will be secured to the respective bights of the cable.
- 15 The ends of the cable may pass around this clamp (not shown) and then be held by the clamps C. Of course, various forms of clamps might be attached to the ends of the cable but this does not form the subject matter of the
- 20 present invention.

Near the lower ends of the guide arms 10 and 10' is secured a bracket 23 to which is pivotally connected, as at 24, the brace rod 25 which, in turn, is provided with a slot 26 at its upper end which passes over a bolt 27 mounted in a clamp 28. This clamp is shown in detail in Fig. 3 and consists of a body portion with the lower leg 29 and the upper portion 30 which is provided with a slot 31 in which fits the flange 32 of the walking beam 1. It will be understood that there are two of these braces 25 and likewise, of course, two clamps, one on each side of the walking beam extending to the guide arms. The clamps 28, after the machine has been placed in position, will be moved along the walking beam to adjust the guide arms or beam hanger through lock bolts 33, as will be readily understood.

The guide arms may be strengthened by cross braces, such as at 34, and on the outer faces of 40 these arms may be seen the guide pins 35, a pair being shown near the lower ends of the said arms and one about midway the arms directly in front of the brace 34.

As heretofore mentioned, the parts are all preferably electrically welded, such as the saddle bearing or brackets 23, the braces 34, the guide arms 10 and 10', and the supporting plates 11 and 12, thus providing a fabricated structure of great strength.

50 From the foregoing, it will be seen that with my present beam hanger, it may be readily attached to the end of any walking beam and especially to a steel fabricated beam like that illustrated and that the angle of the hanger may be quickly and readily adjusted by a movement of the small clamps 28 which may then be locked in place. Again, when it is desired to swing the beam hanger out of the way, the rods 25 will be slipped off the bolt 27 to thus allow the rods 60 or tubing to be pulled from the hole without interference with this beam hanger.

Finally, the supporting cable is in two bights, each of which passes through the supporting

trunnion, with further safety means in the way of clamps above the trunnion, so that if either bight should break the remaining bight will still support the rod.

Many slight changes might be made in the construction hereinbefore set forth without in any manner departing from the spirit of the invention.

Having thus described my invention, what I claim as new and desire to secure by Letters Patent is:

1. A beam hanger including a mounting adapted to be secured on a walking beam, a trunnion in said mounting, arcuate guide arms hung near the opposite ends of said trunnion, means secured near the lower ends of said arms and adapted to also be secured to said walking beam to position the hanger, a crown extending above said trunnion, a cable supported on said crown and extending down said arms, the lower ends of said cable adapted to be secured to a clamp, and means secured to the cable above the trunnion to prevent the entire cable from slipping from said crown should one of the bights of the cable be parted.

2. A beam hanger including a trunnion, means for mounting the trunnion on a walking beam, a crown above said trunnion, guide arms hung from said trunnion, a cable resting in said arms and passing through said trunnion and extending across the crown thereof, and means secured to the cable above the trunnion to prevent the cable if broken from passing entirely through said trunnion.

3. In combination with a walking beam having outwardly extending flanges, a mounting on the end of the walking beam, a trunnion in said mounting, a crown above said trunnion, the said trunnion being perforate near its opposite ends, guide arms supported from said trunnion, means clamped to the flanges of said walking beam for adjustably positioning the guide arms with angular respect to the walking beam, a cable threaded over said crown and through the trunnion and extending down along said guide arms, and means above the trunnion for preventing the cable from leaving said hanger even though one bight of the cable should become parted.

4. In combination with a fabricated metal walking beam, clamps adjustably secured along said walking beam, a trunnion mounted near the outer end of the walking beam, means for holding the trunnion in place, a crown supported by the trunnion, cable bearings in the form of guide arms, means for bracing the arms with respect to each other, braces extending from the lower portion of said arms to said clamps, a cable having its opposite ends threaded through said trunnion and supported on said crown, and further clamps secured to the cable above said trunnion to thereby prevent the loss of said cable.

HENRY A. WINLAND,
